UNITED STATES PATENT OFFICE.

FREDERICK KOSKUL, OF WILLIAMSPORT, PENNSYLVANIA.

DESIGN FOR THE SURFACE ORNAMENTATION OF WALLS.

SPECIFICATION forming part of Design No. 18,428, dated July 3, 1888.

Application filed March 17, 1888. Serial No. 267,577. Term of patent 14 years.

To all whom it may concern:

Be it known that I, FREDERICK KOSKUL, of Williamsport, Lycoming county, Pennsylvania, have invented and produced a new and original Design for the Surface Ornamentation of Walls, &c., of which the following is a specification.

The accompanying photographs, Figures 1, 2, and 3, are plan views of my design, showing the same in one row, two rows, or multiple rows of the same pattern.

A is an elevation in the form of a quadrangular pyramidal frustum, having rounded or curved faces, as B. Parallel to the sides of the elevation A appear rounded or convex elongated elevations C, the extremities L of which are inclined or beveled.

At the corners of the design appear rectan-

gular pyramidal elevations D, each having rounded or convex sides. Between the elevation A and the adjacent elevations C is a channel, I. Between each elevation D and the adjacent ends of the elevations C are channels J K.

Upon the summit of the pyramidal elevation A are four lenticular depressions, which produce the appearance of a cross, as shown at M.

I claim—

The design for surface ornamentation of walls, &c., substantially as herein shown and described.

FREDERICK KOSKUL.
